UNITED STATES PATENT OFFICE.

ARTHUR O. AUSTIN, OF BARBERTON, OHIO, ASSIGNOR, BY MESNE ASSIGNMENTS, TO THE OHIO BRASS COMPANY, OF MANSFIELD, OHIO, A CORPORATION OF NEW JERSEY.

INSULATOR CAP.

Application filed April 7, 1921. Serial No. 456,875.

To all whom it may concern:

Be it known that I, ARTHUR O. AUSTIN, a citizen of the United States, residing at Barberton, in the county of Summit and State of Ohio, have invented certain new and useful Improvements in Insulator Caps, of which the following is a specification.

This invention relates to supporting members for insulators, and especially to caps for insulators of the suspension type, and has for its object the provision of devices of the class named which shall readily accommodate themselves to the conditions of stress to which they are subjected and which shall be of improved construction and operation.

The invention is exemplified in the combination and arrangement of parts shown in the accompanying drawings and described in the following specification, and it is more particularly pointed out in the appended claims.

In the drawings—

Fig. 1 is a plan view of an insulator cap embodying one form of the present invention;

Fig. 2 is a section on line 2—2 of Fig. 1;

Fig. 3 is a plan view of an insulator cap showing a modified form of the invention;

Fig. 4 is a section on line 4—4 of Fig. 3;

Fig. 5 is a fragmentary section on line 5—5 of Fig. 3;

Fig. 6 is a section similar to Figs. 2 and 4, showing another form of the invention; and

Fig. 7 is a section similar to Fig. 6, showing a different modification of the invention.

Insulators are commonly made of porcelain or similar material having a relatively high ultimate strength in compression, but having comparatively low strength in tension and shear. Such insulators are commonly provided with some form of metallic supporting member, such as a metallic cap which fits over a portion of the dielectric member. The dielectric member is secured within the cap by holding material, such as Portland cement, which transmits the load carried by the insulator from the dielectric member to the cap. As explained in my prior application, Serial No. 314,875, filed August 2, 1919, it is desirable that some means be provided for effecting a yielding connection between the insulator and cap

in order to provide a proper distribution of the load transmitted by the securing material. It is also desirable to provide means for taking care of the differences in expansion and contraction of the dielectrics and metallic members under changing temperature conditions. In my prior application referred to above, I have shown various means for securing certain of these characteristics. In the invention shown in the present application the cap itself is arranged to provide elasticity so that it will yield to the forces to which it is subjected and thus prevent subjecting the dielectric member to dangerous stresses.

It is desirable that the cap shall yield both in the direction of the load to which the insulator is subjected in order to distribute the load along the cap in the longitudinal direction of the insulator and also that it shall yield circumferentially to prevent dangerous stresses on the dielectric member due to unequal contraction and expansion resulting from temperature changes.

A substantial thickness of the walls of the cap is necessary to resist the action of weather when the caps are in use and also to facilitate proper and easy casting where the caps are made of cast metal. The thickness must ordinarily be such that there is not sufficient elasticity to prevent dangerous stresses in the dielectric. A cap made according to the present invention, however, provides the desirable elasticity in its walls while retaining sufficient thickness thereof.

In Figs. 1 and 2 an insulator cap 10 is provided with a socket member 11 for receiving a supporting pin in the usual manner and the interior of the cap is provided with ribs or projections 12 for holding cement or other securing material in place therein. The lower edge of the cap is crimped or corrugated to provide a rim 13 which will yield when subjected to a load transmitted thereto from the dielectric member which is cemented within the cap. The rim 13 is divided by a series of slits 14 spaced circumferentially thereabout to permit yielding of the rim in a circumferential direction and thus prevent undue gripping of the dielectric member which would give rise to dangerous stresses. The portion of the cap 10 spaced inwardly from, or above

the rim 13 may also be provided with openings or slits 15 extending through the wall of the cap. Various arrangements and spacing of the slits 15 may be employed, 5 there being two rows of such slits shown in the form of the invention illustrated in Fig. 2, the rows being arranged one above the other and the slits being circumferentially spaced about the cap and preferably positioned to alternate with one another.

In Figs. 3 and 4 a form of cap is illustrated in which, in addition to the slits 14, the rim 13 is provided with perforations 16 which extend substantially parallel with the 10 wall of the cap and penetrate the outer portion of the rim 13. It will be seen from Fig. 5 that these perforations may be readily punched or drilled through the extending portion of the rim 13 and that any number 15 of such perforations may be employed so as to give the desired resiliency to the rim, and where the perforations cut into the interior of the cap at the fold of the corrugations as shown in Fig. 5, the stiffness of the 20 corrugations will be materially reduced to provide a marked yielding effect.

In the form of the invention shown in Fig. 6 the wall of the cap 10 is provided with a plurality of series of slits 17, the 25 slits of the different series being arranged to overlap one another at their ends, as shown, so that the metal is divided up into bars or strips which will bend when subjected to stress. The actual movement, of course, is slight, but is relatively sufficient to overcome the effect of unequal contraction and expansion under temperature changes or to equalize the distribution of load stresses. The arrangement of the slots shown in Fig. 30 will assist in permitting expansion of the cap in the direction of the axis of the insulator, but will be most effective, of course, in providing for circumferential expansion.

Another arrangement of perforations is shown in Fig. 7 in which the wall 10 of the insulator is provided with any desired number of perforations 18. The perforations 18 may be punched or drilled or cast in the cap and are preferably staggered relative to one 35 another to provide an expanded metal effect so as to produce yielding both longitudinally of the insulator and circumferentially of the cap. The rim 13 may also be provided with perforations 19 similar to perforations 16 in Fig. 5 and additional perforations 20 may also be made in the rim 13 to secure still further yielding action. It will be apparent that the amount of elasticity of the cap may be regulated by the number of perforations 40 and that the perforations may be arranged to secure a greater degree of elasticity in any direction desired. The amount of the elasticity in various portions of the cap may also be regulated by providing the proper num-

ber of openings suitably distributed. While 65 the perforations are illustrated in the drawings as extending entirely through the walls of the insulators, it will be understood that they may extend only partially through the walls, leaving thin portions to close the openings, but which are sufficiently reduced in thickness to permit of the requisite yielding action.

I claim:—

1. An insulator cap having a plurality of 75 series of perforations in the wall thereof spaced circumferentially about said cap and arranged in staggered relation relative to one another.

2. An insulator cap having the wall 80 thereof corrugated to form a rim at the edge of said wall and having perforations extending through said rim to render said rim elastic, the material of said rim forming a closed wall surrounding each of said perforations.

3. An insulator cap having the wall 85 thereof bent to form a corrugation and having perforations extending through said corrugation from one exterior face to the 90 other exterior face thereof so that both ends of said perforations open on the exterior of said cap.

4. An insulator cap having a wall thereof 95 bent to form an outwardly projecting corrugated flange at the edge thereof and having perforations extending through said flange to render said flange elastic, said perforations opening at their opposite ends on the exterior of said cap and arranged to cut 100 into the interior of said cap, intermediate the ends thereof.

5. An insulator cap having the wall 105 thereof corrugated to form a flange at its edge said wall having overlapping perforations therein spaced from the edge thereof, said flange being perforated at spaced points about the circumference of said cap.

6. An insulator cap having the wall 110 thereof corrugated to form a rim at the edge of said wall and having perforations extending through said rim to render said rim elastic, said perforations being spaced inwardly from the outer periphery of said rim and having both ends thereof opening 115 externally of said rim.

7. An insulator cap having a plurality of 120 series of circumferentially spaced openings in the walls thereof, said openings being staggered both circumferentially of said cap and in the direction transversely to the circumference thereof to permit expansion of said cap circumferentially and in an axial direction.

In testimony whereof I have signed my 125 name to this specification on this 10th day of March, A. D. 1921.

ARTHUR O. AUSTIN.
